OPERATING DEVICE FOR PERFORATING
BLADES USED IN THE FORMS OF
PRINTING MACHINES

Eugen Fröhlich, Zurich, Switzerland

Application May 17, 1934, Serial No. 726,186
In Germany June 24, 1933

3 Claims. (Cl. 164—98)

This invention relates to a device of the kind mounted together with perforating blades in the form of a printing machine for operating said blade in co-operation with an impression cylinder (for instance as indicated in the co-pending application Serial No. 726,187) or other suitable element, and the invention consists in the provision of a casing containing a spring-controlled operating bolt which operates the blades and which for this purpose is advanced at each printing operation or periodically by a cam wheel mounted on a rotary shaft, the latter being rotated intermittently through the medium of a pawl and ratchet mechanism and a plunger which is depressed at each printing operation and which also acts directly on the bolt for advancing the latter whenever such movement is initiated by the cam wheel.

Fig. 1 of the accompanying drawings represents a plan view of a device according to the invention with removed top cover;

Fig. 2 is a side view of the device;

Fig. 3 is a section on the line III—III of Fig. 1;

Fig. 4 is a side view showing the bolt in advanced position;

Fig. 5 is a plan view of the operating shaft;

Fig. 6 is a side view of the plunger;

Fig. 7 is a side view of the bolt;

Figs. 8, 9 and 10 are views showing different forms of cam wheels intended for a periodic advance of the operating bolt;

Fig. 11 is a plan view like Fig. 1 of a modified form of the device, and

Fig. 12 is a section on the line XII—XII of Fig. 11.

The device comprises a casing 1 fitted with a cover 2 and adapted to be mounted in the form of a printing machine together with perforating blades by means of which the printed web is perforated. The blades are normally maintained in inoperative position within the form and are moved into operative position as they pass under the impression cylinder. This is effected by means of a plunger 3 which projects from the casing 1 for contact either with the impression cylinder or other suitable element and which advances an operating bolt 15 for the displacement of a slide by means of which the appertaining blade or blades are brought into operative position. The slide is held between guides 23 which engage in a recess 22 in the casing 1 in register with an aperture through which the reduced end 16 of the bolt is adapted to advance. A spring 18 bears against a shoulder 17 on the bolt and tends to maintain it in retracted position. The

regular or periodic advance of the bolt is effected through the medium of a cam wheel 13 which is exchangeably mounted on the free, hexagonal end of a shaft 5 supported rotatably in a partition 6 and in one of the walls of the casing. The cam wheel is provided with teeth adapted to engage a shoulder 19 on the bolt. The shaft is also fitted with a ratchet wheel 7 having twelve teeth for engagement with a pawl 8 pivotally connected to the plunger 3. A spring 10 bears against the ratchet wheel and acts as a detent. Another spring 11 bears against the pawl and holds the latter in contact with the wheel. Both springs are fastened by means of screws 9. The plunger 3, which is controlled by a spring 4, carries a bevelled member 21 which is normally in position to engage in a notch 24 in the bolt 15. The latter has also an inclined cam face 20 with which the member 21 is adapted to co-operate for advancing the bolt after it has been started by the cam wheel.

The plunger 3, on striking against its abutment, will be depressed by the latter, and the movement of the plunger will be initially transmitted by the pawl 8, shaft 5, and cam wheel 13 to the bolt 15. After a partial movement of the latter the cam face 20 of the bolt will be engaged by the bevelled member 21 of the plunger, and the further advance of the bolt will thereupon be effected by the plunger directly, thereby relieving the pawl 8 and the cam wheel of work and preventing undue wear of the teeth. When the plunger recedes after having passed the abutment, the cam wheel will be retained by the spring 10 in its advanced position, and the shoulder 19 is then free to move over the back of the tooth which advanced it, so that the bolt can be restored by the spring 18 to its initial position (see Fig. 4).

In the arrangement shown in Fig. 2, the cam wheel 13 is provided with the same number of teeth as the ratchet wheel 7, and the bolt will therefore be advanced for perforating the web at each printing operation. Cam wheels of different shapes may be employed so that the perforation will be effected periodically in various ways. Fig. 8 shows a wheel 13' presenting double spacing of the teeth so that perforation of the web will take place at every other printing operation. Where there is no tooth on the cam wheel for engagement with the shoulder 19, the cam wheel moves idly, and the member 21 of the plunger enters the notch 24 in the bolt and secures the latter against displacement. Fig. 9 shows another form of cam wheel 13'' by means of which every third printing operation is carried

out without perforation, and Fig. 10 shows a wheel 13" by means of which two successive printing operations accompanied by perforation, are followed by two operations without perforation. Other arrangements may be resorted to.

Figs. 11 and 12 show an arrangement wherein the pawl and cam wheel are relieved of work from the commencement of the movement. This is effected by providing the plunger 3 with a 10 slideable cam member 25 which is supported by a spring 26 and which remains in permanent contact with the cam face 20 of the bolt 15. The spring 26 is too weak to move the bolt initially by itself, and therefore, if the cam wheel should move idly during a printing operation, the member 21 of the plunger enters the notch 24 in the bolt and secures the latter against displacement. Otherwise the movement of the bolt will be initiated by the joint action of the cam wheel and 15 of the member 25, and further movement will be carried out by the engagement of the member 21 with the cam face 20.

The cam wheel is covered by a sliding door 14 which can be removed for an exchange of 20 wheel.

Owing to the simplicity of the device it can be made very small and yet strong enough to meet all requirements.

I claim:

30 1. A device for operating perforating blades mounted in the form of a printing machine, comprising a casing, a spring-controlled operating bolt in said casing, a shaft in the casing, a ratchet wheel on the shaft, a spring-controlled plunger projecting from the casing, a pawl on the plunger adapted to co-operate with said

ratchet wheel for imparting partial rotation to the shaft at each depression of the plunger, a toothed cam wheel mounted exchangeably on the shaft, a shoulder on the bolt adapted to co-operate with the teeth of said cam wheel for advancing the bolt, and means enabling the plunger to act directly on the bolt for advancing the latter whenever such advancing movement is initiated by the cam wheel.

2. A device for operating perforating blades 10 mounted in the form of a printing machine, comprising a casing, a spring-controlled operating bolt in said casing, a spring-controlled plunger projecting from said casing, a rotatable shaft in the casing, a ratchet wheel on the shaft, a 15 pawl on the plunger adapted to co-operate with said ratchet wheel for imparting partial movement to the shaft at each depression of the plunger, a toothed cam wheel mounted exchangeably on the shaft, a shoulder on the bolt adapted 20 to co-operate with the teeth of said cam wheel for advancing the bolt, a bevelled member carried by the plunger, and a cam face on the bolt adapted to be engaged by said bevelled member for advancing the bolt after its movement has 25 been initiated by the cam wheel, the bolt having a notch adapted to be engaged by said bevelled member for locking the bolt if no movement is imparted to the latter by the cam wheel on a depression of the plunger.

3. The structure claimed in claim 2 in combination with a spring-controlled cam member carried by the plunger and adapted to engage permanently with the cam face of the bolt for assisting the movement of the latter.

EUGEN FRÖLICH.
